Attorney

UNITED STATES PATENT OFFICE

JOHN O. WESNER, OF STEWART MANOR, NEW YORK

CASEMENT-WINDOW RETAINING ROD

Application filed March 4, 1930. Serial No. 433,090.

This invention relates to new and useful improvements in retaining rods for casement windows and has for its primary object to provide, in a manner as hereinafter set forth, 5 a rod of this character which is adjustable longitudinally and which is permanently and pivotally secured at its opposite end to the window frame and window sash in a manner to permit swinging movement of said window.

Another important object of the invention is to provide a retaining rod for casement windows embodying a pair of telescopically connected sections having coacting means 15 associated therewith for frictionally securing the sections in adjusted position.

Another very important object of the invention is to provide a retaining rod for casement windows of the character set forth embodying a construction and arrangement whereby said rod may be expeditiously secured in adjusted position while the opposite ends thereof are connected to the window frame and window sash.

Other objects of the invention are to provide, in a manner as hereinafter set forth, a casement window retaining rod of the character described which will be simple in construction, strong, durable, efficient in its use 30 and which may be manufactured at low cost.

All of the foregoing and still further objects and advantages of the invention will become apparent from a study of the following description, taken in connection with the 35 accompanying drawings wherein like characters of reference designate corresponding parts throughout the several views, and wherein:

Figure 1 is a view in top plan of the retaining rod secured in operative position on the window frame and sash.

Figure 2 is a longitudinal sectional view taken substantially on the line 2-2 of Figure 1 looking in the direction indicated by the arrows.

Figure 3 is a perspective view illustrating the element constituting the frictional locking means for securing the sections of the rods in adjusted position.

Referring to the drawings in detail, it will

be seen that the numeral 1 designates the frame of a casement window, the sash 2 of which is mounted for swinging movement on said frame through the medium of the hinges 3.

The retaining rod constituting this invention is designated generally by the reference numeral 4 and comprises an inner, elongated tubular section 5 which is mounted for swinging movement in a horizontal plane on the sill 6 of the frame 1 through the medium of the horizontally disposed brackets 7 and the pivot pins 8. A closure plug 9 is inserted in the inner end of the tubular section 5 and is retained therein by the pivot pin 8 which extends transversely therethrough.

The outer end of the tubular section 5 has mounted thereon a threaded cap 10 through which is slidably disposed what will be hereinafter referred to as the outer section of the 70 rod 4 which is designated generally by the reference numeral 11. The outer section 11 comprises an elongated rod 12 which extends slidably through the cap 10 and projects into the tubular section 5. The inner end of the rod 12 is provided with a reduced, integral threaded shank 13 having an annular flange 14 formed thereon intermediate its ends. A pair of elongated, substantially semi-circular complementary brake shoes 15 are mounted 75 on the inner end portion of the rod 12 for longitudinal sliding movement in the tubular inner section 5 and the opposed sides of said brake shoes, at one end portion thereof, are suitably recessed as seen best in Figures 2 and 80 3 to rotatably receive therebetween the adjacent end portion of the rod 12, the shank 13 and the flange 14. The flange 14 is adapted to disposition in an enlarged portion of the recess formed in the opposed sides of the 85 brake shoes to cause longitudinal movement of said shoes with the rod 12. The opposed sides of the brake shoes 15 are also provided with recesses 16 having the inclined cam surfaces 17 and a resilient, substantially U- 90 shaped actuating member 18 is threaded for longitudinal movement on the shank 13 and disposed in the complementary recesses 16 for engagement with the cam 17.

The outer end of the rod 12 has connected 100

thereto by means of a swivel joint 19, an extension 20 which is pivotally connected to a bracket 21 mounted on the free end portion of the sash 2 of the casement window. The 5 swivel joint 19 permits rotation of the rod 12 relative to the extension 20 and this constitutes a very important feature of applicant's invention.

In use, the parts are assembled in the manner illustrated in the drawing, and when it 10 is desired to swing the casement window, the rod 12 is rotated on the extension 20 in a direction to shift the resilient spreader 18 away from the cam surfaces 17 of the brake shoes 15. The pressure of said shoes against the inner walls of the tubular sections 5 is thus reduced sufficiently to permit sliding movement of said shoes and the window may 15 thus be swung to any desired position. The direction of rotation of the rod 12 is then reversed in a manner to move the spreader 18 between the cam surfaces 17 and spread the shoes 15 into engagement with the inner walls of the tubular sections 5 and the sections of 20 the rod are thus frictionally secured together in adjusted position. The shoes 15 are preferably retracted just enough to permit sliding movement of the same in the tubular section 5 but the same are preferably maintained 25 in engagement with the walls of said tubular section 5 under sufficient pressure to permit rotation of the same with the rod 12. If desired, suitable longitudinally extending co-acting ribs and channels may be provided on 30 the shoes and the inner wall of the tubular section 5 to positively prevent rotation of 35 said shoes with the rod 12.

The swivel connection 19 which joins the 40 rod 12 to the supporting extension 20 permits the locking or unlocking of the shoes 15 while the opposite ends of the rod are secured to the sash and frame of the window, as will be apparent and, as before stated, this is a 45 most desirable and important feature of this invention.

It is believed that the many advantages 50 of a casement window retaining rod constructed in accordance with this invention will be readily understood, and although the preferred embodiment of the invention is as 55 illustrated and described, it is to be understood that changes in the details of construction may be had which will fall within the scope of the invention as claimed.

55 What is claimed is:—

A casement window retaining rod of the 60 character described comprising a pair of telescopic sections, one section comprising an elongated cylinder mounted for swinging movement on the window frame, the other section comprising an elongated rod extending slidably and rotatably into the cylinder, a reduced, integral, threaded extension on the inner end of the rod, an annular flange 65 formed on the extension, a pair of comple-

mentary brake shoes mounted on the extension on diametrically opposite sides thereof and having opposed recesses therein for the reception of the flange, said shoes further having their opposed faces provided with 70 complementary recesses having inclined cam surfaces, a resilient spreader member threaded for longitudinal movement on the extension and engageable with the cam surfaces in a manner to shift the brake shoes laterally to 75 frictionally engage the walls of the cylinder, another extension swivelly mounted on the outer end of the rod and a bracket hingedly connected to the free end of the second named extension and to the sash of the window.

In testimony whereof I affix my signature.
JOHN O. WESNER.
